UNITED STATES PATENT OFFICE

168,919

APPLIQUE OR THE LIKE

Richard G. Williams, Palm Springs, Calif., assignor to Ralph L. Nafziger, Palm Springs, Calif.

Application November 3, 1951, Serial No. 17,244

Term of patent 14 years

(Cl. D3—9)

To all whom it may concern:

Be it known that I, Richard G. Williams, a citizen of the United States, residing in Palm Springs, Riverside County, California, have invented a new, original, and ornamental Design for an Applique or the like, of which the following is a specification, reference being had to the accompanying drawing forming a part hereof.

Fig. 2 is a cross-sectional view of that shown in Fig. 1 taken along the line 2—2.

I claim:

The ornamental design for an applique or the like, substantially as shown.

RICHARD G. WILLIAMS.
